UNITED STATES PATENT OFFICE

106,907

DESIGN FOR AN ARTICULATED RAILWAY
CAR OR SIMILAR ARTICLE

Isaac C. Barlow and Edmund D. Campbell, Berwick, Pa., and Otto Kuhler, Grantwood, N. J., assignors to American Car and Foundry Company, New York, N. Y., a corporation of New Jersey

Application August 29, 1936, Serial No. 64,640

Term of patent 14 years

To all whom it may concern:

Be it known that we, Isaac C. Barlow and Edmund D. Campbell, citizens of the United States, residing at Berwick, county of Luzerne, State of Pennsylvania, and Otto Kuhler, a citizen of the United States, residing at Grantwood, county of Bergen, State of New Jersey, have invented a new, original, and ornamental Design for an Articulated Railway Car or Similar Article, of which the following is a specification, reference being had to the accompanying drawings, which form a part thereof.

Figure 1 represents, in perspective, an articulated railway car or similar article embodying the design;

Fig. 2 is a front end elevation of the railway car;

Fig. 3 is a rear end elevation of the railway car;

Fig. 4 is a side elevation of the front end portion of the railway car, and

Fig. 5 is a side elevation of the rear end portion of the railway car.

The present design comprises as the principal and dominating features thereof, the forwardly inclined head end portion of a railway car or similar vehicle combined with a substantially centrally arranged nosing strip which extends rearwardly for a distance along the roof of the train. In addition the train includes at its front end and near the lower portion thereof a plurality of super-imposed ornamental widely flaring V-shaped configurations, the end of one of said V-shaped configurations continuing along substantially the full length of the sides of the train.

We claim:

The ornamental design for an articulated railway car or similar article as shown, and described.

ISAAC C. BARLOW.

EDMUND D. CAMPBELL.

OTTO KUHLER.
